PICTURE HOLDER

Carroll N. Cross, Middleboro, Mass.

Application November 18, 1937, Serial No. 175,308

8 Claims. (Cl. 40—152)

This invention relates to picture holders and mounts which include a picture receiving and holding body and means in the back thereof to permit the insertion of a picture.

5 Heretofore such holders have been provided with an open edge through which the picture was customarily inserted, or in the alternative, a flap, hinged about score lines on the back of the holder has been provided for this purpose.

10 Both of these forms of prior construction have been objectionable in actual use. The open edge of a mount permits dirt and dust to reach the enclosure, while the formation of flaps heretofore used involves extra steps in the manufacture,

15 and in use imposes excessive strain on the back of the holder or mount.

It is therefore, an object of this invention to provide a picture holder or mount which is closed around its marginal edges and into which a pic-

20 ture or the like may be inserted through a passage in the back which is normally closed by a flap adapted to swing freely about its pivot without imposing any strain on the body of the holder.

25 Further objects and advantages of the invention will become apparent as the description thereof proceeds in view of the drawing forming a part hereof, in which like reference numerals indicate like parts, and in which;

30 Fig. 1 is a face view of the picture holder involving the invention;

Fig. 2 is a view taken from the back of the holder to show the means provided for inserting a picture and having a corner broken away to 35 show underlying structure;

Fig. 3 is a sectional view on line 3—3 of Fig. 2;

Fig. 4 is a sectional view on line 4—4 of Fig. 2; and,

Fig. 5 is an enlarged sectional fragment corresponding to the lower end of Fig. 4.

40 The holder, generally indicated at 10, comprises a backboard 12, a marginal spacing board 13 and a face-board 14. The outer marginal edges of the backboard, the spacing member and the face-board may be substantially coextensive.

45 The backboard 12, the marginal spacing member 13 which is cut throughout the body thereof for the purpose of providing a picture and glass receiving well, and the face-board 14 are superimposed upon each other and are bound together along the entire margin by means of a flexible covering member 15. This flexible covering may extend over the entire back of the holder, around the edges, and over the front of the face-board 50 or, as shown in Fig. 5, it may extend over the

face-board 14, around the marginal edges of the holder, and terminate on the backboard where the exposed edges may be neatly concealed by means of a second decorative covering member 16.

5 It will be noted that the cut-out in the face-board 14 which constitutes the picture display window is smaller than the cut-out forming the well in the spacing member 13. Thus there is provided means for securely and positively holding a picture or a picture and a covering transparent medium 18 such as glass.

The picture may be inserted between the glass 18 and the backboard 12 but in the preferred practice of the invention the picture is first 15 mounted on a relatively stiff mounting insert 20 which is provided to facilitate the insertion and withdrawal of the picture as well as for the purpose of displaying the picture to best advantage.

A picture inserting opening is formed in the 20 backboard 12 by providing a flap portion 22 formed by cutting through the backboard on a line parallel to one of the edges as along the line 23 and along the parallel lines 24. The line 23 extends from a point intermediate the width of 25 the spacing member 13 on one side of the holder to a point intermediate the width of the spacing member 13 on the other side of the holder. The parallel lines 24 extend from the line 23 through the outer edge of the backboard 12. As a consequence of this construction, the flap 22 may be 30 swung freely around the lower marginal edge of the holder 10 while using the flexible binding material 15 as a pivot. The inner movement of the flap 22 is limited by its contact with the 35 spacing member 13 at each end thereof. Turn buttons 28 which are attached to or extend through the backboard 12 are provided to hold the flap 22 in its normally closed position.

40 In this construction is provided a convenient means for inserting a picture into a holder of the class described and one which does not weaken the relatively thin and inexpensive material from which these holders are usually constructed. At the same time an opening is provided which gives 45 quick access to the interior thereof throughout at least the width defined by the well in the spacing member 13.

The invention having been described in a preferred form is not to be limited in its use other 50 than the limitations which may be imposed thereon in the following claims.

I claim:

1. A picture holder constructed of lightweight flexible stock comprising an enclosure for a pic- 55

- ture, a picture inserting passage in the back of said holder extending inwardly from one edge thereof, a closure flap for said passage, a flexible binding strip constituting the sole means for joining said closure flap to said holder adjacent the margin thereof to permit angular movement of said flap, and means carried by the back of said holder for maintaining said flap in normally closed position.

5. A picture holder constructed of lightweight flexible stock comprising a backboard, a marginal spacing member having a picture receiving well therein, a face-board having a display window, a flexible member extending about the marginal edges of said backboard, spacing member and face-board whereby the same are joined and sealed about their margins, a picture inserting passage in said backboard extending inwardly from one edge thereof, a closure flap for said passage joined to said holder solely by said flexible member along the outer margin thereof to permit angular movement of said flap, and means carried by said backboard for maintaining said flap in normally closed position.

6. A picture mount constructed of lightweight flexible stock comprising a face-board and a backboard, a flap member severed from said backboard, a flexible binding member extending over at least a portion of said backboard and constituting a sole hinge for said flap at one outer edge thereof thereby permitting angular movement of said flap to a position beyond the margins of said mount.

7. A picture mount constructed of lightweight flexible stock comprising a face-board and a backboard, a flap member severed from said backboard, a flexible binding member extending about at least one edge of said boards and over said backboard and constituting a sole hinge for said flap at one outer edge thereof thereby permitting angular movement of said flap about a marginal edge of said mount to a position there-

8. A picture mount constructed of lightweight flexible stock comprising a backboard and a face-board adapted to position a picture or the like against said backboard, a picture display window in said face-board, a flap member severed from said backboard and having its outer edge coincident with the outer margins of said boards, a flexible binding member extending around the edges of said board at the region of said flap and constituting a sole hinge for said flap at the outer edge thereof thereby permitting movement of said flap about said edge to a position beyond the margins of said mount.
